UNITED STATES PATENT OFFICE.

MAY CLEMENT, OF NEW YORK, N. Y.

STOCKING-PROTECTOR.

1,292,259.

Specification of Letters Patent. Patented Jan. 21, 1919.

Application filed May 29, 1916. Serial No. 100,306.

To all whom it may concern:

Be it known that I, MAY CLEMENT, a citizen of the United States, residing at New York, in the county of New York and State of New York, have invented certain new and useful Improvements in Stocking-Protectors, of which the following is a specification.

The present invention has for its object 10 to provide as a simple article of manufacture a stocking protector which is designed for the purpose of protecting the knee of the stocking from undue strains incident to the flexing of the knee of the wearer, while 15 at the same time affording reinforcement against injury by the hose supporters.

To assist in a comprehension of the advantages of this invention it may be stated that in the use of hose, especially where 20 made of material of fine texture there is a tendency for the knee portion to adhere to the flesh particularly where the latter is moist from perspiration, and this prevents the material from adjusting itself in its 25 yielding action, when the knee is bent, by relatively slipping on the surface of the knee. The result is often a bursting of the knee portion of the hose or perhaps breaking of one or more threads of the material 30 that finally "runs" down. This result is more or less assisted by the longitudinal strains imparted by the attachment of the hose supporters at one or more points and it is to overcome these disadvantages that 35 the present invention is produced. I am quite well aware that it has been heretofore proposed to provide a knee protector as particularly adapted for use by children in the form of a pad which is attached to the 40 leg of the wearer on top of the stocking but this is for the purpose of preventing wear of the material, whereas it is important to note my protective device is applied to the leg beneath the stocking and interposed between the flesh and the stocking material, 45 the purpose or function being entirely different as explained above.

For a full understanding of the present invention, reference is to be had to the 50 following description and the accompanying drawings, in which:

Figure 1 is a perspective view showing the application of my invention in coöperative relation with the hose, portions of the 55 latter being broken away to show the arrangement more clearly.

Fig. 2 is a rear elevation of the protector.

Fig. 3 is a similar view of a slightly modified form of the protector:

Fig. 4 is a fragmentary sectional view 60 showing more clearly the folding of the stocking engaging portion for reinforcing the stocking top.

Throughout the following detail description, and on the several figures of the drawings, similar parts are referred to by like reference characters.

Referring to the drawing and specifically describing this article, the numeral 1 designates the body portion of the protector 70 which is of any suitable strong fabric material and it may be of any suitable configuration. It is comprehended, of course, to make the protector in different sizes and of material of different texture as well as color, 75 these phases of the question being immaterial, however, from the standpoint of this description.

The upper portion of the protector body is designed to be folded outwardly upon the 80 top of the stocking and for this purpose the upper portion is provided with lateral extensions or flaps 2, 2 so as to substantially surround the top portion of the stocking to enable the attachment of one or more hose 85 supporting elements. The lower portion or extremity of the protector is provided with an elastic band 3 stitched thereto to engage about the leg of the wearer just below the knee so as to prevent the displacement of 90 the lower portion of the protective device. As shown at 4 each lateral edge of the body of the material is caught into a fold in stitching the hem about the body, this providing a slight bagging of the material at an 95 intermediate point to accommodate for the bulging of the knee when attached in place.

As shown in Fig. 1 of the drawing, this article is first applied to the knee portion against the flesh and beneath the stocking 100 which is drawn thereover, the elastic band 3 surrounding the leg as above mentioned, just below the knee and the upper end portion of the protector being folded back over the top of the stocking 5. The hose supporters 6 are 105 then attached to the protector and stocking top, the former constituting reinforcement for preventing injury by the gripping elements of fastening devices of the hose supporters. The upper portion need not necessarily be folded over the hose as mentioned 110 for the material may easily be caught in with

the hose when the supporters are attached to the latter, at the discretion of the user.

In Fig. 3 is illustrated a slightly modified form of the device in which the body is somewhat more elongated than the preferred form shown in Fig. 2, said body being provided at an intermediate point of each edge with a lateral extension or ear 7, said extensions being connected by an elastic strap 8 which will engage about the leg at the knee thereof. The top portion of this form of the protective device is provided with the lateral flap extensions and the lower with the elastic band as above described with reference to the preferred form.

It will be obvious from the foregoing description that the article may be very cheaply and easily manufactured though the expense, of course, would depend upon the character of material used in its embodiment.

Having thus described my invention, what I claim as new is:

1. The combination with a stocking, of a protector of flexible material disposed within the stocking so as to be interposed between the flesh of the wearer and the stocking, the upper and lower edges of said material being relatively thin so as not to project materially from the surface of the flesh, and means for holding said protector against accidental displacement while permitting the relative movement of the fabric of the stocking thereover, at the knee portion in the flexing of the knee.

2. The combination with a stocking, of a

protector of fabric material, the body of said material being relatively broad at its upper portion to substantially surround the leg and constitute detachable reinforcing means 40 for the stocking, said material of the body narrowing toward the central portion, stocking engaging means for holding the upper portion against displacement, and leg engaging means attached to the lower portion 45 of the protector for holding the latter against accidental displacement while permitting relative movement of the stocking thereover.

3. The combination with a stocking and 50 supporting means therefor, of a protector of fabric material adapted to be arranged beneath the stocking, said protector being provided with a foldable end portion for folding over the top of the stocking and with 55 which folded portion the supporting means aforesaid is engageable, and leg engaging means attached to the protector to hold the same in operative position.

4. As a new article of manufacture, a protective device for stockings comprising a body having its upper portion provided with lateral foldable extensions for folding engagement with the stocking, and a leg engaging member secured to said body portion. 60

In testimony whereof I affix my signature.

MAY CLEMENT.
